(57) **CLAIM**

The ornamental design for profiled pipes, as shown and described.

DESCRIPTION

FIG. 1 is a top, left, front perspective view of profiled pipes showing a new design therefor, the opposite view being identical;

FIG. 2 is a view similar to FIG. 1 of a second embodiment of the invention; and,

FIGS. 3 and 4 are end views of the respective first and second embodiments of the invention.

The pipes are shown fragmented in FIGS. 1 and 2 to indicate indeterminate length.
